L. E. WOOD.
WINDOW FIXTURE,
APPLICATION FILED MAR. 10, 1921.

1,391,599.

Patented Sept. 20, 1921.

UNITED STATES PATENT OFFICE.

LOUIS E. WOOD, OF FARRELL, PENNSYLVANIA.

WINDOW-FIXTURE.

1,391,599.

Specification of Letters Patent. Patented Sept. 20, 1921.

Application filed March 10, 1921. Serial No. 451,119.

To all whom it may concern:

Be it known that I, Louis E. Wood, a citizen of the United States, residing at Farrell, in the county of Mercer and State of Pennsylvania, have invented certain new and useful Improvements in Window-Fixtures; and I do declare the following to be a full, clear, and exact description of the invention, such as will enable others skilled in the art to which it appertains to make and use the same.

This invention relates to an improved window fixture, and it has for one of its objects to provide a device of this class which embodies separate and independent means for supporting the usual curtain, means for supporting additional draperies, sometimes known as lambrequins, and the usual means for supporting a shade or blind.

The principal object of the invention is to generally improve upon similar devices of this class by producing one of extreme simplicity and durability which can be placed in position for use by unskilled hands, one which is such in construction that it permits the curtains and draperies to be swung away from the window to an out of the way position so that the window can be easily cleaned or repaired, this being also advantageous in that it allows free entry of air and prevents the curtains from being blown out of the window and becoming soiled as oftentimes happens.

Another object of the invention is to provide fixtures of the type under consideration which are such in construction that easy hanging of the curtain and drapery on the same is insured, such construction being advantageous in that it permits all of the swinging parts of the device to be moved to one side of the window, or it permits the curtain supporting arms only to be moved independent of one another and to the respective adjacent sides of the window.

A further and important object of the invention is to provide a fixture of this class which embodies one or more brackets for attachment to the window frame, these brackets including horizontal laterally extending arms beveled at their outer ends and provided near these ends with stop pins, the curtain and drapery supporting members associated with the brackets including tubular adjusting sleeves of such construction as to permit placement thereof on the bracket arms to be accomplished easily and greatly

facilitated, the tubular sleeves including guide slots for co-action with the stop pins to prevent relative rotation of the parts and to limit the outward sliding movement of 60 the sleeves.

Other objects and advantages of the invention will be apparent during the course of the following description.

In the accompanying drawings forming a 65 part of this specification and in which like numerals are employed to designate like parts throughout the same:

Figure 1 designates a top plan view of a fixture constructed in accordance with this 70 invention, the same being shown attached to a window frame to illustrate the relative position of the parts thereof.

Fig. 2 is a front elevational view thereof with a portion of one of the connecting tubes 75 broken away and shown in section.

Fig. 3 is an enlarged elevational view looking toward one end of the fixture.

Fig. 4 is a sectional view taken substantially on the plane of the line 4—4 of Fig. 3. 80

Fig. 5 is an enlarged sectional view of one of the tubular arms of the drapery supporting member, the section being taken substantially on the plane of the line 5—5 of Fig. 1. 85

In carrying out the invention, I make use of a pair of brackets in the form of stampings, the same including attaching plates 1 for connection to the window frame, these plates being provided near their lower ends 90 with conventional means 2 for supporting a shade or blind, being provided at their opposite upper ends with spaced horizontal forwardly extending rigid arms 3. The arms 3 as better seen in Fig. 5, have their 95 under faces beveled as indicated at 4, these bevels being at their outer ends. Disposed near the beveled ends of said arms and arranged on the lower faces of the latter are lateral stop-pins or projections 5. These 100 parts constitute what are to be here termed the brackets.

It has been before intimated that my improved fixture embodies separate and independent means for supporting the usual lace 105 curtains and also includes like means for supporting drapery such as is sometimes hung on the inside of the curtain. The curtain supporting member is designated generally by the numeral 6, while the drapery supporting member is designated by the numeral 7. Both of these members are dupli-

cates and it is therefore unnecessary to describe them separately. Therefore, the same reference characters will be employed to designate like parts of the two members 6 and 7. To this end, it will be seen that each member is made up of a pair of relatively long hollow rods 8, which, when the fixture is in use, extend at right angles from the bracket arms 3 and cross-wise of the window. Headed pins 9 are riveted or otherwise secured to the outer ends of said rods and heads of these pins are pivoted between fork-arms 10 of adjustable sleeves 11. A careful examination of the sleeves just referred to will disclose the fact that they are designed to be slidably mounted on the bracket arms 3, and as before stated, it is desired that these sleeves be of such construction that their engagement with said arms will be facilitated. I therefore provide each of said sleeves at their inner ends with substantially semi-circular extensions 12 and in their underfaces with elongated guide slots 13. This construction and arrangement permits the sleeves to be angled as indicated in dotted lines in Fig. 5 so that by using the beveled ends of the bracket arms as fulcrum points, they may be slid onto said arms in such a way that the stop-pins 5 can be easily engaged in the guide slots. After the sleeves are in the position shown, they are prevented from rotating on the bracket arms and their outward sliding movement is limited. With this construction and arrangement, it will be seen that I have devised a simple and quick detachable connection which will permit easy and ready assembling of the fixture. It is also to be noted that a considerable range of adjustment of the members 6 and 7 may be accomplished with this construction and arrangement. The weight of the curtain causes the sleeves 11 to bind frictionally on the bracket arms so that once adjusted, they will be retained in this position and prevented from sliding. Since the curtain and drapery supporting members embody two arms, it is necessary to provide means for connecting the free ends of these arms together to prevent accidental swinging of the curtain or drapery. The means preferably employed for accomplishing this result is in the form of comparatively long tubes 14, these being fitted over the free ends of the rods 8 in the manner disclosed in Figs. 1 and 2. With this construction, it will be seen that when it is desired to swing the curtain or drapery away from the window, it is only necessary to slide the connecting tubes onto one of the rods 8 so as to disconnect the free ends of the latter.

In use, the brackets are secured on the window frame in the usual way. Then, the sleeves 11 are angled as indicated in Fig. 5, and positioned on the bracket arms 3 for

sliding movement, the stop pins 5 extending through and engaging the guide slots 13 so as to prevent rotation of the sleeves on the bracket arms and limit their outward movement. Furthermore, I wish to again direct attention to the fact that particular emphasis is to be laid on the novel construction and arrangement which permits of quick and easy assembling of the sleeves 11 on the bracket arms. At this point, I also wish to state that with the construction and arrangement shown, one or both of the members 6 and 7 may be employed or omitted as desired. After the members 6 and 7 are in place, the curtain and drapery can be placed thereon in the usual way and the ends of the rods 8 connected together as indicated in Fig. 1. Since the connecting tubes 14 are of considerable length, they not only serve to permit considerable range of adjustment to be had for adapting the device to windows of various widths, but they serve to greatly reinforce the rods 8. After the curtains and draperies are in position, it will be seen that they can be moved closer to or farther from the window as desired by simply sliding the sleeves 11 on the bracket arms 3. As before stated, the weight exerted on the members 6 and 7 is sufficient to cause the sleeves 11 to frictionally bind on the bracket arms to prevent accidental sliding of said sleeves. It is hardly necessary to again state that the brackets or means indicated by the numeral 2 is designed to accommodate and support the usual shade or blind shown in dotted lines.

From the foregoing description, it will be seen that I have devised an extremely simple and advantageous fixture for windows which serves to support curtains, draperies, and blinds. The parts of the fixture are such that they can be easily and readily assembled for use by unskilled hands and when the fixture is out of use, the parts thereof may be arranged in a compact package for easy transportation. Furthermore, with my construction and arrangements, the curtains may be swung open and against the wall so that they will be in an out-of-the-way position when the window is being cleaned or repaired. In this way, the curtains and draperies are prevented from being soiled from dirty hands or water. Ordinarily, it is necessary to entirely remove the curtain in order to accomplish this task. Hence, it will be seen that much time and labor will be saved with my construction and arrangement, and yet my fixture is so simple that it can be manufactured and sold at a cost slightly more than those now in use.

A careful consideration of the foregoing description taken in connection with the accompanying drawings is thought to be sufficient to enable persons skilled in this art to obtain a clear understanding of the same.

Therefore, a more lengthy description is deemed unnecessary.

Advantageous and effective results are practically insured with the construction 5 and arrangement herein shown and described. Hence, this construction and arrangement is taken as a preferred embodiment of the invention. However, I wish it to be understood that various minor changes 10 within the scope of the subjoined claims may be resorted to.

I claim:

1. A fixture of the type set forth comprising a bracket for attachment to a window 15 frame, including an attaching plate and a fixed forwardly extending horizontal bracket arm beveled at its outer end and provided near this end with a lateral stoppin, and a curtain supporting member in- 20 cluding a right-angularly disposed tubular slotted sleeve adapted to slide on said arm and having a portion thereof cut away at its inner end to permit it to be detachably engaged with said arm, said stop-pin to ex- 25 tend through the slot in the sleeve and limit the sliding thereof and also prevent rotation thereof on said arm.

2. A combined curtain and drapery sup- 20 porting fixture comprising a pair of brackets

for connection to a window frame, said 30 brackets including attaching plates, each carrying inner and outer spaced parallel rigid forwardly extending horizontal cylindrical arms beveled on their underfaces at their outer ends and provided near these 35 bevels with lateral stop-pins; a curtain supporting member adapted to be associated with said inner bracket arms; and a drapery supporting member to be supported by the outer bracket arms; each of said members 40 being composed of two separate rods adapted to extend toward each other and cross- wise of the window, and short sleeves having pivotal connection with the outer ends of said rods and adapted to slide on said arms, 45 said sleeves having portions of their upper sides cut away at their inner ends and having elongated slots in their underfaces terminating at one end near the outer ends of the extended portions and permitting them 50 to be detachably engaged with the aforesaid bracket arms so that said stop-pins will extend through said slots; and means for detachably connecting the inner ends of the rods together. 55

In testimony whereof I have hereunto set my hand.

LOUIS E. WOOD.
